UNITED STATES PATENT OFFICE.

JAMES H. BENNER, OF AKRON, OHIO.

COMBINED RAIL TIE AND FASTENER.

1,156,581.

Specification of Letters Patent. Patented Oct. 12, 1915.

Application filed August 21, 1914. Serial No. 657,926.

To all whom it may concern:

Be it known that I, JAMES H. BENNER, a citizen of the United States of America, residing at Akron, in the county of Summit and State of Ohio, have invented certain new and useful Improvements in Combined Rail Ties and Fasteners, of which the following is a specification, reference being had therein to the accompanying drawing.

This invention relates to combined rail tie and fastener and has for its object to provide, in a manner as hereinafter set forth, a tie for supporting a track rail and further a supporting tie having means associated therewith for fastening the track rail in position with respect to the tie without the employment of nuts and bolts.

Further objects of the invention are to provide a combined rail tie and fastener which is simple in its construction and arrangement, strong, durable, efficient and convenient in its use, readily set up and comparatively inexpensive to manufacture.

With the foregoing and other objects in view the invention consists of a novel construction, combination and arrangement of parts, as hereinafter more specifically described and illustrated in the accompanying drawings wherein is shown an embodiment of the invention, but it is to be understood that changes, variations and modifications can be resorted to which come within the scope of the claims hereunto appended.

In the drawings wherein like reference characters denote corresponding parts throughout the several views:—Figure 1 is an end elevation of a rail fastener. Fig. 2 is a side elevation. Fig. 3 is a longitudinal sectional view of one end of a tie. Fig. 4 is a transverse sectional view of a tie. Fig. 5 is a top plan view of a tie, broken away. Figs. 6 and 7 are enlarged detailed perspective views of one of the clamping members. Fig. 8 is an enlarged detailed perspective view of a section of the rail tie.

The tie which is formed from a metallic body includes a bottom 1, a pair of side walls 2, which at the end are of greater height, as at 3, than their intermediate portions.

Each of the side walls 2 is provided throughout with an inwardly extending flange and the said flanges of the said side walls 2 are indicated at 4, 5. Each of the flanges 4, 5, near each of its ends, (only one end shown) is cut away to provide a notch

6 having oppositely extending inclined end walls 7, 8. The flange 4 is connected to the flange 5 by a transverse coupling member 9 which is disposed centrally with respect to the opposed notches 6 and divides each notch 6 into a pair of recesses each provided with an inclined end wall and a straight end wall, the latter being indicated at 10, and the former provided by one of the inclined walls 7, 8. The coupling member 9 centrally thereof is formed with a pair of centrally disposed lateral projectors 11, 12 each inclined downwardly and which has each end under cut as indicated at 13. The coupling member 9 is adapted to support a track rail and the latter includes a base 14, web 15, and head 16. The coupling member 9 is of the same width as the width of the base 14 and the lateral projectors 11, 12, 75 project outwardly with respect to the longitudinal edges of the base 14.

The track is clamped to the tie through the medium of two pairs of rail fasteners and the rail fasteners of each pair are indicated by the reference characters 17, 18. The rail fasteners 17, as well as the rail fasteners 18, include a head 19, having one end thereof beveled as at 20, and the other plane as at 21. One side of the head 19 is formed with a clamping jaw 22, having a plane inner wall 23, and plane bottom wall 24 and an upward inclined top wall 25. The other side of the head 19 is formed with a clamping jaw 26, having a plane lower wall 27, and a plane upper wall 28. Formed integral with the bottom of the head 19, at the inner end thereof, is an inclined shank 29 which forms the continuation of the beveled end 20 and greatly decreases in width 95 downward. The shank 29 terminates in an inwardly projecting right angular extension 30 which is peripherally threaded. The threads upon the extension 30 of the fastener 17 are oppositely disposed with respect to 100 the threads upon the extension 30 of the fastener 18 thereby setting up right and left threads which are adapted to be engaged by a turn buckle 31 whereby when the latter is shifted, the fasteners 17, 18 will be moved apart or drawn toward each other, depending in what direction the buckle 31 is shifted.

When the rail fasteners are set up with respect to the tie and base 14, one wall of the jaw 26 bears against an inclined wall of 110 a recess, while the plane end wall 23 of the jaw 22 is positioned against the plane end

wall 10 of the recess. The upper wall 28 and lower wall 27 of the jaw 26 straddles a flange 4, 5, depending with which flange the fastener associates, and the upper wall 25 of the jaw 22 over-laps the base flange 14, while the lower wall 24 of the said jaw 22 over-laps the coupling member 9. When the rail fasteners are in position the shank 17 engages the under cut ends of the projections 11, 12. The turn buckle 31 provides means for shifting the rail fasteners to snugly engage with respect to the flanges 4, 5, coupling member 9, and base 14.

10 The ends of the tie body (only one is shown) have arranged therein curved bridge members 32, which connect the enlarged ends 3 of the side walls 2 together.

What I claim is:—

20 In a device of the class described, a rail fastener comprising a head, the sides of which are designed to form clamping jaws,

and the one end wall thereof being beveled, one of said jaws having flat right angular bottom, inner side and top walls, and the other of said jaws having flat right angular bottom and inner side walls and an upwardly and outwardly beveled top wall, a downwardly and outwardly inclined extension formed on the referred to end wall of the head and providing a continuation for the beveled end wall and having a threaded lateral projection at the free end thereof, and a turn buckle for engagement with said threaded projection to connect the same with another member.

30 In testimony whereof I affix my signature in the presence of two witnesses.

JAMES H. BENNER.
